COMPACTOR HOUSING

Helmut A. Maass, Hartford, Wis., assignor to
M-B-W, Inc., Slinger, Wis.

Filed Aug. 11, 1971, Ser. No. 171,024

Term of patent 14 years

Int. Cl. D15—04, 99

U.S. Cl. D60—1

Fig. 4

Fig. 5

FIG. 1 is a side elevational view of a compactor housing embodying my new design.

FIG. 2 is a top plan view of the compactor housing shown in FIG. 1.

FIG. 3 is a side elevational view of the compactor housing shown in FIGS. 1 and 2 and of the side opposite that shown in FIG. 1.

FIG. 4 is a front elevational view of the compactor housing shown in FIG. 1.

FIG. 5 is a rear elevational view of the compactor housing shown in FIG. 1.

FIG. 6 is a side and front perspective view of the compactor housing shown in FIG. 1.

The broken line showing is for illustrative purposes only.

I claim:

The ornamental design for a compactor housing, as shown and described.
